(57) **CLAIM**

The ornamental design for a cigar holder, as shown and described.

DESCRIPTION

FIG. 1 is a left side perspective view of the cigar holder shown in an open position.

FIG. 2 is a right side perspective view of the cigar holder shown in a closed position.

FIG. 3 is a top plan view of the cigar holder shown in an open position.

FIG. 4 is a front elevation view of the cigar holder shown in an open position; and,

FIG. 5 is a right side elevation view of the cigar holder shown in an open position.

For convenience of illustration, the lines have been omitted from the recessed areas of the cigar holder in FIG. 3.
